SUPERHEATER BOILER

George P. Jackson, Flushing, N. Y., assignor to
Combustion Engineering Company, Inc., New
York, N. Y.

Application November 20, 1935, Serial No. 50,642
In Great Britain December 10, 1934

2 Claims. (Cl. 122—480)

This invention relates to improvements in boilers of the kind wherein a furnace chamber with steam generating tubes on its walls is surrounded by an up-pass in which there is a superheater shielded by a bank of convection-heated boiler tubes. The improvements have for their main object to prevent over-superheating and to produce a maximum of superheat with a minimum of boiler heating surface preceding the superheater.

In carrying out the invention this main object is attained by providing a by-pass around the said up-pass in which the superheater is located, which by-pass contains some of the convection-heated boiler surface. Preferably the bank of tubes constituting the convection-heated boiler surface extends from a lower header first in a more or less inclined direction across the furnace chamber and then substantially vertically to an upper header connected with the steam and water drum. The by-pass encompasses the vertical portion of the convection-heated boiler surface and has at its upper part a damper-controlled communication with the up-pass, preferably above the level of the superheater. The setting of the damper controlling this communication determines the proportion of the heating gases which flow by way of the by-pass and above the superheater to the off-take.

The accompanying drawing represents a vertical section through the upper part of a boiler constructed in accordance with the invention.

The furnace chamber 1 is of well-known construction adapted for firing by turbulent combustion and having walls protected by steam generating tubes 2 connected to the steam and water drum 3 by downcomers 4 and risers 5. The convection-heated surface of the boiler comprises a bank of generating tubes 6 extending from a lower header 7 at slight upward inclination across the greater part of the width of the chamber 1 and then vertically to an upper header 8. One side of this upper header is turned upwardly as at 8', thus facilitating the provision of the tubes 10 connecting this header with the drum 3. The circulatory system is completed by the downcomers 11 and 12 between the drum 3 and the lower header 7.

The by-pass 13, which is a feature of the invention, is formed by a partition 14 extending through the upper part of the chamber 1 in front of the vertical portion of the tubes 6. The upper portion of the partition constitutes a damper 15. The downcomers 12 are protected from heat by refractory tiles 16 which form another partition in the chamber; the space between the partitions is an up-pass 17 for the products of combustion which flow thence through the down-pass 18 to the off-take 20.

Tiles 21, in part supported by the tubes 4, form a wall of the down-pass 18 in which an economizer 22 of any known kind is accommodated; for this may be substituted a primary stage superheater or a reheater and in either case by-pass dampers 5 may be provided.

In the up-pass 17 is placed the superheater 23 and it will be seen that when the damper 15 is closed the whole of the products of combustion flow over the inclined portions of the convection tubes 6 and the superheater and that when the damper 15 is more or less open more or less of the said products flow through the by-pass 13 and across the top of the up-pass 17 substantially without imparting heat to the superheater. Preferably, the ratio of heat absorbing surface comprised by the vertical parts of the tubes 6 to that of the parts thereof below the superheater and the surface of the latter is such that the gases flowing through the by-pass 13 are cooled by the vertical portion of tubes 6 so that their temperature is approximately the same as that of the products which have passed over the superheater.

What I claim is:

1. In a boiler; a furnace chamber; a superheater positioned above said chamber in a path of gases flowing therefrom; baffle means disposed substantially vertically at one side of said superheater and spaced from one side of the boiler setting to form a by-pass for gases to flow from said chamber to the boiler off-take without contact with the superheater; a steam generating bank comprising rows of tubes extending across the furnace chamber below said superheater with portions of the tubes in all rows of the bank extending substantially vertically through said by-pass, the heat absorbing capacity of said vertical tube portions being substantially equal to that of said superheater together with the tube portions below the latter; and damper means at the upper end of said by-pass for controlling the flow of gases through said by-pass.

2. In a boiler; a furnace chamber; a superheater above said chamber; baffle means disposed substantially vertically at one side of said superheater and spaced from one side of the boiler to form a by-pass for gases to flow from said chamber to the boiler offtake without contacting the superheater; rows of generating tubes extending across the furnace chamber below said superheater and having portions thereof extending upwardly through said by-pass and the heat-absorbing surfaces of which are so related to the heat absorbing surfaces of the superheater and of the tube portions below the latter that gases flowing through the by-pass are cooled to substantially the same extent as those flowing over the superheater.

GEORGE P. JACKSON. 60
